DOOR LOCK FOR AUTOMOBILES

Joseph Drzewiecki, Detroit, Mich.

Application August 31, 1936, Serial No. 98,659

3 Claims. (Cl. 70—149)

My invention relates to door locking mechanism primarily intended for use in automobiles, and its principal object is to provide a door locking mechanism of the type in which, when the 5 door is locked, the handle is free to rotate without operating the latch or releasing the door in any way. The present construction provides means actuated through the lock for connecting the handle with the latch mechanism and for disconnecting the same at the proper time, that is to say, when the door is locked and the key withdrawn.

Another object of my said invention is to provide a device of the character referred to which 15 has combined with it means for operating the lock from the inside of the vehicle.

Another object of my invention is to provide an improved type of latch bolt combined with a special form of dovetail opening in which the 20 latch bolt engages and which is provided with resilient cushioning means whereby the door may be closed quickly or even violently without producing appreciable noise or damage to the door and its associated parts.

25 A further object of my invention is to provide a door lock which is simple in construction and economical to manufacture, and which may be installed in various ways to suit the style of vehicle to which it is applied and which may be 30 fitted to various types of doors without excessive cutting and weakening of the door and the co-acting pillar.

With these and other objects in view, the invention consists in the improved construction, 35 arrangement, and combination of parts which will be hereinafter fully described, reference being had to the accompanying drawings, which illustrate a preferred embodiment thereof, in which drawings—

40 Figure 1 is a sectional plan view of the complete lock provided with a horizontally swinging latch to be hereinafter described.

Figure 2 is an end view of the same.

45 Figure 3 is a side elevation, the outer plate being cut away.

Figure 4 is a section on line 4—4 of Figure 5 showing the cushioned latch socket, or keeper.

Figure 5 is a horizontal section through the 50 center of the main handle.

Figure 6 is a section on line 6—6 of Figure 5.

Figure 7 is a vertical section on line 7—7 of Figure 5 showing the operation of the locking devices on the main shaft with the horizontal latch.

Figure 8 is a sectional end view taken on line 8—8 of Figure 11.

Figure 9 is a horizontal section through the center of the main shaft illustrating the operation of the handle clutch means. 5

Figure 10 is a section on line 10—10 of Figure 9.

Figure 11 is a section on line 11—11 of Figure 7 showing the lower rod which operates the horizontal latch.

Figure 12 is a fragmentary view showing an 10 alternative form of spring for operating the latch mechanism.

Figure 13 is a fragmentary view corresponding to Figure 7 showing certain of the parts in alternative positions. 15

Like characters designate corresponding parts throughout the several views.

Referring more particularly to Figures 1 to 11, inclusive, 1 designates the wooden portion of an automobile door which is partly enclosed in the 20 sheet metal coverings 2 according to the usual practice in regard to automobile doors. 3 is the wooden portion of a pillar having the steel covering 4 which forms the abutment for the door. The pillar, however, may sometimes be entirely 25 of metal construction, according to the type of vehicle for which it is intended. 5 is the latch-operating handle having secured to or integral therewith a hollow stem 6, and within this handle is contained a tumbler mechanism 7 which, in 30 co-operation with the key 8, forms the conventional locking means by which the door is secured in a manner to be hereinafter explained.

The stem 6, rotatably mounted within a bushing 9 secured to the door, is retained in position 35 endwise by means of the set screw 10 shown in Figure 6 which is mounted in a fixed lug not shown and engages in an annular groove 11 in the stem 6. Concentric with the stem 6 and secured in the wooden portion 1 of the door is a 40 hollow member 12 within which is slidably mounted a bushing 13 having a closed end 14, between which and the closed end 15 of the member 12 is a helical compression spring 16 which is adapted to force the bushing 13 in the 45 direction of the stem 6. The bushing 13 is provided with a key-like projection 17, shown more particularly in Figures 6 and 7, which is rotatably mounted in a cavity 18 in the member 12 and is adapted, under certain conditions, to engage in a notch 19 in the inner end of the stem 6, so that rotation of the handle will at that time cause corresponding rotation of the bushing 13 within the member 12. Upon the inner face of the wooden portion 1 of the door is mounted a 50 55

plate 20 to which is secured a box-like structure 21 and between the members 20 and 21 is a collar 22 which fits closely around the bushing 13 and has a key-way which engages with the projection 17 of the bushing, as shown more particularly in Figure 7, so that rotation of the bushing will cause corresponding rotation of the collar and vice versa. Upon the collar 22 is a tongue 23 with which engages one end of a rod 24 for which purpose the rod has a U-shaped portion 25, shown clearly in Figure 11, which partly surrounds the tongue, as will be understood. The rod 24 has also an arcuate portion 26 by which it operates the latch bolt. The latch bolt, designated 27, and shown in more complete detail in Figure 11, is formed from sheet metal and provided with an angular abutment 28 which, when the door is locked, engages a corresponding abutment 29 in the socket 30 of the keeper, the latter being secured within the pillar 3 in the well known manner. The latch bolt 27 is supported in a housing 31 pressed up from sheet steel and of wedge-like shape in end view, as shown in Figure 8, and having a rounded end 32, the socket 30 being of similar shape so that when the door is closed the housing 31 fits snugly within the socket. The latch bolt 27 is pivoted at 33 to the housing and is normally urged outwards so as to engage the socket 30 by means of the coil spring 34, one end of which engages the inner surface of the housing while the other presses against the inner face of the hollow latch bolt member. The latch bolt is also provided with a flanged portion 35 in which is a circular opening 36. In this opening engages the end of the arcuate portion 26 of the rod 24, so that longitudinal movement of the rod in the direction indicated by the arrow 37 in Figure 11 will cause the latch bolt to be retracted from its socket, 40 against the action of the spring 34, thus allowing the door to open.

Projecting from the inner face of the door is an auxiliary handle 38 secured by screw 39 to a short shaft 40 rotatably mounted in a bushing 41 secured in the member 1, and upon the reduced end 42 of the shaft is secured a lever arm 43 having therein a pair of slots 44, 45. On one end of the rod 24 is a bent portion 46 which engages in the slot 45, as shown clearly in Figure 11. By this arrangement, movement of the handle 38 can be employed to open the door from the inside by pulling upon the rod 24 and retracting the latch bolt from its socket as above explained. The slot 45, however, allows movement of the handle 38 to a certain extent without acting upon the rod 24, providing a leeway for a purpose which will be hereinafter explained.

In Figures 5 and 6 the bushing 13 is shown in such position that the projection 17 is disengaged from the slot 19 in the stem 6 of the handle, so that rotation of the handle 5 will not produce any movement of the latch bolt, but at this time the latch bolt may be operated by the auxiliary handle 38 as above explained. When, 65 however, the bushing is moved into the position shown in Figures 9 and 10, bringing the projection 17 into engagement with the slot 19, movement of the handle 5 in one direction will cause rotation of the bushing and, through the tongue 70 23 of the collar 22, will cause longitudinal movement of the rod 24 in the direction of the arrow 37 in Figure 11, so as to retract the latch bolt in the manner above explained.

Disengagement of the projection 17 from the 75 notch 19 so as to allow the handle 5 to rotate

freely without acting upon the latch mechanism may be effected in two ways, in one case from the inside of the door and in the other case from the outside.

Disengagement from the outside is effected by 5 means of the key 8 rotating the barrel 71 of the tumbler mechanism 7. This barrel carries an eccentric pin 72 which, when the barrel is rotated, impinges upon the end of a flat bar 61 which extends through the center of the stem 6 10 and makes contact with the end of the bushing 13, moving it, against the action of the spring 16, into the position shown in Figures 5 and 6. The bar 61 may be guided by any suitable means such as the pins 62. In order to retain the bushing 13 in this position, there is provided a spring pawl 47, shown more clearly in Figures 7 and 10, one end of which is fixed in a stud 48 upon the plate 20 while the other end engages in a notch 49 in the upper face of the bushing. It will be 20 observed that, due to the fact that the pawl is located in the same plane as the collar 22, it is necessary to cut away the collar so as to allow the pawl to reach the notch 49, and when the pawl is resting in the notch it also rests against 25 the marginal edges 59 of the cut-away portion, this condition being shown in Figure 7, from which figure it will be observed that rotation of the collar around the bushing will cause the end of the pawl 47 to be lifted out of engagement 30 with its co-acting notch, as shown in Figure 13. It will be observed also that rotation of the collar may be effected by pulling upon the rod 24 which engages the tongue 23 and in this manner the proper manipulation of the auxiliary handle 38 will cause release of the bushing and permit the projection 17 to re-engage the notch 19 under the action of the spring 16, provided that the eccentric pin 72 is turned to a position diametrically opposed to that in which it is shown 40 in Figure 5.

Disengagement of the handle from the inside of the door is effected by proper manipulation of the auxiliary handle 38 through the rod 51, one end of which engages in the slot 44 of the member 43 while the other end terminates in a pin 52 engaging the lever 53 pivoted at 54 to the member 12, the arrangement being shown more clearly in Figures 5 and 9. The lever 53 is provided with a tongue 55 which engages in a notch 56 in the bushing 13 so that movement of the rod 51 in the direction indicated by the arrow 56', Figure 5, will cause the lever 53 to be moved in such manner that the bushing 13 will be retracted against the action of the spring 16, disconnecting it from the handle as above explained.

It should be here explained that, due to the fact that the rods 24 and 51 are connected to the lever arm 43 through slots 45 and 44, respectively, movement of the said arm may cause the rod 24 to be pulled in the direction of the arrow 37 in Figure 11, so as to release the latch bolt, without effecting any movement of the rod 51, while movement of the arm in order to push upon the rod 51, causing it to travel in the direction indicated by the arrow 56' in Figure 5 and withdraw the bushing 13 from engagement with the handle, may be effected without causing any movement of the rod 24. The lengths of the slots 44 and 45 and the proportions of the other elements of the mechanism are so arranged that movement of the auxiliary handle 38 through its full travel will cause disengagement of the pawl 47 and also withdrawal of the latch bolt 27, but by moving the said handle through a por- 70 75 80 85 90 95

tion only of its travel the pawl may be disengaged without withdrawing the latch bolt, thus permitting engagement of the bushing 13 with the main handle to permit operation of the latch bolt from the outside. Due to this arrangement of the slots, also, the door may be closed by pushing upon it from the outside, causing the latch bolt 27 to be first pushed inwards and then allowed to move outwards under the action of its 10 spring to engage the socket 30, this being effected without damage to the mechanism since at this time the end 46 of the rod 24 moves freely in the slot 45. The rod 24 is provided with a helical compression spring 57, one end of which presses 15 against the U-shaped portion 25 on the rod, while the other end re-acts against the inner face of the box-like structure 21. In some cases a spiral spring 58 may be substituted as shown in Figure 12, the said spring engaging a collar 59 upon the 20 rod.

The mechanism above described is so adjusted that, while operation of the member 13 through the inside handle 33 will cause the pawl 47 to engage it and hold it in disconnected position, 25 yet operation of the said member by turning of the key of the tumbler in the outside handle will not permit the pawl 47 to engage, since the longitudinal movement of the member 13 will be less in this case. If, however, the member 13 is dis- 30 engaged by the inside handle and the occupants then leave the car, slamming of the door will push the latch bolt inwards and rock the collar 22 into the position shown in Figure 13, lifting the pawl 47 out of engagement and allowing the member 13 to be moved outwards by its spring 16 ready for the outside locking operation.

In the embodiment of my invention herein shown I employ a special cushioning device for preventing undue impact between the latch housings and the latch sockets and to avoid rattling of the parts when in transit. This device, shown 40 in Figure 4, consists essentially of a plate 63 which fits loosely within a slot in the housing 30, the said plate being backed by a cushion of rubber or other resilient material 64 occupying a cavity 65 in the wood filling 3 of the pillar 6.

While I have herein described and shown a preferred embodiment of my invention, it will be understood by those skilled in the art that the same may be modified to suit any particular requirement without departing from the spirit of 50 my invention.

Having thus described my said invention, what

I claim and desire to secure by Letters Patent of the United States is:

1. A door latch mechanism comprising a housing, a latch bolt pivoted in said housing and adapted to engage a co-acting keeper socket, a 5 collar rotatably mounted in said housing, a tongue upon said collar, a rod coupling said tongue and said latch bolt in co-operative relation, a handle having a hollow stem arranged co-axially with said collar, a notch in said stem, a bushing rotatively connected to said collar and 10 slideable longitudinally therein, a projection upon said bushing adapted to engage said notch, and resilient means normally urging said projection into engaged position. 15

2. A door latch mechanism comprising a housing, a latch bolt pivoted in said housing and adapted to engage a co-acting keeper socket, a collar rotatably mounted in said housing, a tongue upon said collar, a rod coupling said tongue and said latch bolt in co-operative relation, a handle having a hollow stem arranged co-axially with said collar, a notch in said stem, a bushing rotatively connected to said collar and 20 slideable longitudinally therein, a projection upon said bushing adapted to engage said notch, resilient means normally urging said projection into engaged position, and lock-controlled means 25 within said handle for holding said projection out of engagement. 30

3. A door latch mechanism comprising a housing, a latch bolt pivoted in said housing and adapted to engage a co-acting keeper socket, a collar rotatably mounted in said housing, a tongue upon said collar, a rod coupling said tongue and said latch bolt in co-operative relation, a handle having a hollow stem arranged co-axially with said collar, a notch in said stem, a bushing rotatively connected to said collar and 40 slideable longitudinally therein, a projection upon said bushing adapted to engage said notch, resilient means normally urging said projection into engaged position, and lock-controlled means within said handle for holding said projection out of engagement, said means comprising a bar 45 slideable axially within said stem and in alignment with said bushing, a tumbler mechanism rotatable within said handle at right angles to said stem and having eccentric means adapted to impinge upon said bar and force said sleeve into disengaged position. 50

JOSEPH DRZEWIECKI.
